GARMENT

Frank Jones, Toronto, Ontario, Canada

Application May 9, 1941, Serial No. 392,617
In Canada September 21, 1940

1 Claim. (Cl. 2-93)

The principal object of this invention is to provide greater flexibility and strain-relief in garments of various types in order to minimize ripping of the seams and to ensure greater comfort and freedom to the wearer.

The principal feature of the invention resides in the incorporation of an elastic strain-relieving strip in direct co-operative association with the main back portions of the garment and in such a manner that the elastic insert will be covered and protected by a loosely overlying portion which greatly enhances the appearance of the garment.

In the drawings

Figure 1 is a back view of a sport type jacket illustrating the present invention applied thereto.

Figure 2 is a view similar to Figure 1 showing the loosely overlying portion of the garment turned outwardly to expose the inserted elastic strip.

Figure 3 is a transverse section through the body portion of the garment.

Figure 4 is a back view representative of a dress, uniform or the like, incorporating the present invention.

In the manufacture of jackets, coats, dresses, doctors' and nurses' uniforms and the like, it is extremely desirable to provide for lateral stretchability, particularly in the back region, in order to provide for greater freedom of movement and at the same time relieving the garment of damaging stresses, while maintaining a garment of a neat snug-fitting appearance.

It has been previously proposed to provide a resilient insert in connection with inner linings of garments in order to compensate for shrinkage or non-stretchability in the lining material, but the resiliency of the garment as a whole was limited to the inherent resiliency of the outer body material of the garment and the present invention has been devised to enable a more resilient construction of the main back portion of a garment irrespective of the lack of stretchability in the garment fabric or of whether the garment is lined or not, and by way of example the invention has been illustrated in Figures 1 to 3 in connection with the construction of a sport jacket, while in Figure 4 the invention is illustrated in connection with a dress, uniform or the like, but it must be understood that it is not limited in this regard as it is equally applicable to jackets or coats of various types, including those worn by nurses, doctors or service station attendants, all of which may be said to com-

prise garments within the meaning of the claims herewith.

In the form of the invention illustrated in Figures 1 to 3 the jacket is provided with back panel portions 1 and 2 spaced apart centrally of the back and seamed at their bottom edges to a waistband portion 3. The panels 1 and 2 may be provided with longitudinal pleats 4 and 5 extending upwardly from the waistline seam 6 with progressively diminishing depth and a tab portion 7 is secured to the waistband 3 by the seam stitching 6 and is seamed at 8 and 9 along its vertical edges to the spaced edge portions 10 and 11 of the back panel portions 1 and 2.

15 A strip 12 of woven elastic fabric or the like is inserted between the spaced edges 10 and 11 and stitched along the longitudinal edges thereof, and the lower extremity is stitched transversely to the upper edge of the tab portion 7, 20 while the upper extremity is stitched to the collar portion of the garment, preferably by incorporation in the collar seam.

The presence of the tab portion 7 will act as a reinforcing agent but if desired this may be eliminated and the lower extremity of the elastic insert anchored directly in the waistband stitching 6.

25 The garment is preferably provided with an outer panel 13 which is incorporated at the upper end in the shoulder and neckband seams and extends downwardly to snugly overlie the elastic insert strip 12, the lower end thereof being preferably secured to the waistband while the longitudinal edges are free.

In the further exemplification of the invention 35 in Figure 4 the dress or other garment is shown formed with inner back portions 10' and 11' spaced apart in the central region from the waist seam 6' to the neck region, the transversely resilient strip 12' corresponding to the strip 12 of Figures 1 to 3, having its longitudinal edges 40 stitched at 8' and 9' to the substantially parallelly spaced longitudinal edge portions 10' and 11' of the back panels 1' and 2'.

The lower extremity of the elastic strip 12' is 45 advantageously anchored by the waist stitching 6' connecting the lower portions of the back panels sections 1' and 2' to the skirt or lower portion 3' of the garment.

An outer central panel 13' is preferably provided, here shown secured at the bottom in the waist seam or stitching 6' and extending upwardly in broad overlapping relation to the back panel portions 1' and 2' and being free of stitched connection therewith for their major length, the 50 upper end of the outer portion 13' being termi-

nated in the neck region and it may advantageously diverge upwardly for incorporation in the shoulder seams 14 either for a portion or the full length of such seams, as may be desired in the styling of the garment.

The elastic strip 12 or 12' is preferably formed of "Lastex" having little or no longitudinal resiliency but having pronounced lateral resiliency so that when transverse stretching strains are placed on the back portions of the garment the edge portions 10 and 11 or 10' and 11' will be free to diverge away from their normal position since they are only resiliently connected by the intervening elastic strip 12 or 12'. The presence of the elastic strip, in being connected in a bridging manner between the edge portions 10 and 11 or 10' and 11' of the back panels 1 and 2 or 1' and 2', will return and hold the edge portions in their proper relation after the strain has been relieved and will prevent bulging.

The overlying portion 13 or 13' will form a covering for the elastic strip 12 or 12' so that the latter will not be exposed to view and it will further serve as a protective covering for the elastic insert to protect the same against excessive wear or exposure to destructive influences.

A garment having an elastic strip incorporated therein in the manner defined will present as neat a fitting appearance as a tight fitting garment but will at the same time provide for remarkable freedom of action. It will moreover be comfortable to wear and will be substantially free from destructive strains which normally greatly shortens the effective life of such garments.

What I claim as my invention is:

10 A garment having the back formed of sections secured throughout the full length of the shoulder seams and having their inward longitudinal edges parallelly spaced apart centrally of the garment and extending downwardly from the neckband to the waist, a covering medium forming an integral part of the garment being secured at the shoulder seams and neckband and loosely bridging the space between said spaced back sections, and a strip of elastic material having its longitudinal edges sewn to the spaced longitudinal edges of said back sections and having the ends secured to the neckband and to the waist, said elastic material being extensible solely in the transverse direction of the garment.
